Allen Gregg
Inventor

By his Atty.
H. H. Peck

United States Patent Office.

ALLEN GREGG, OF SPRINGBOROUGH, OHIO, ASSIGNOR TO HIMSELF AND PERRY GREGG, OF SAME PLACE.

Letters Patent No. 106,576, dated August 23, 1870.

IMPROVEMENT IN WASHING-MACHINES.

The Schedule referred to in these Letters Patent and making part of the same.

To all whom it may concern:

Be it known that I, ALLEN GREGG, of Springborough, in the county of Warren in the State of Ohio, have invented a new and useful Improvement in Washing-Machines; and I do hereby declare that the following is a full and exact description thereof, reference being had to the accompanying drawings and to the letters of reference marked thereon.

Figure 1 is a perspective view of my improved washing-machine, and

Figure 2 represents a central transverse vertical section of the same, taken at $x x$ of fig. 1.

The object of my invention is to furnish such a combination of devices as to cleanse the clothes by repeated compressing of the boiling suds through the articles being washed, as hereinafter explained.

In the drawings—

A denotes the wash-tub, and

B, the furnace beneath it, the latter being connected to the former by the metal bottom of the tub.

The furnace-top serves as the central portion of the bottom of the tub into which the suds and clothes are placed.

Within the tub there are two perforated wings, w , suspended by their arms $a a$ from rods $r r$, supported by uprights $u u$, secured to the sides of the tub.

Near the ends of the tub there are two perforated partitions, $p p'$, the latter being firmly fixed and the former is hinged at its top to the cleats C, one of the cleats being firmly fastened on each side of the tub, seen in fig. 1.

L denote two bent rods, one of which is connected by loop-bolt hinge-joints with each of the wings w , as seen in fig. 2.

These bent rods L pass through the loop in the lower end of a link, which is secured in a slot of hand-lever M by a metal pin, as represented in the drawings.

At one end of the wash-tub a wash-board, I, is secured, as represented in fig. 1.

When it is desired to use the wash-board the perforated hinged partition p is raised upon its hinge, which gives free access to the clothes, represented in fig. 1, and denoted by the letter N.

The furnace B is provided with a suitable pipe, O. The lever M is hinged centrally at one side of the tub, and the slot through which the link S is inserted is elongated so as to give free play to the link when working the lever M up and down by the hands of the operator.

The clothes to be washed are placed between the wings p and p' and the wings w , which are suspended, as above described; and the operation is effected by continuously raising the lever M and forcing it down; which, through the means of the hinged rods L and link S, will compress the clothes and force the suds through them, and thence through the perforations of the partitions $p p'$.

The action of the water in returning to the central part of the tub will cause the bulk of clothes to be partially turned over, and in their new position a second pressing operation is given, and this process being repeated several times will effectually cleanse the articles from all impurities.

A suitable spigot may be applied at any proper location to draw off the water from time to time, until the articles are ready to be removed from the tub to a wringer.

By using my machine the double process of washing and boiling is effected at the same time.

It will be observed that my arrangement of compressing levers is such as to enable the washer to exert great force in compressing the articles during the last part of the downward movement of the lever M.

Having fully described my new washing-machine, What I claim as my invention, and desire to secure by Letters Patent, is—

The combination of the perforated suspended pressing wings w , perforated partitions $p p'$, hinged rods L, link S, and lever M, arranged and operating conjointly, substantially as and for the purpose described.

In testimony whereof I have hereunto set my hand this 31st day of May, A. D. 1870.

ALLEN GREGG.
